Primary Examiner—Louis S. Zarfas**Assistant Examiner**—Eric Watterson**Attorney, Agent, or Firm**—Finnegan, Henderson, Farabow, Garrett & Dunner, L.L.P.**[57]****CLAIM**

The ornamental design for a combined toilet basin, toilet seat and seat cover, as shown and described.

DESCRIPTION

FIG. 1 is a right side elevational view of a combined toilet basin, toilet seat and seat cover embodying our design, the opposite side being a mirror image;

FIG. 2 is a rear elevational view;

FIG. 3 is a front elevational view;

FIG. 4 is a top plan view;

FIG. 5 is a bottom plan view; and,

FIG. 6 is a perspective view of the front and right side thereof.
